[57] CLAIM

The ornamental design for a bottle, as shown and described.

DESCRIPTION

FIG. 1 is a front elevational view of a bottle embodying our new design, the rear elevational view being the same;

FIG. 2 is a top plan view thereof;

FIG. 3 is a bottom plan view thereof;

FIG. 4 is a front elevational view of a second embodiment of the bottle, the rear elevational view being the same; and

FIG. 5 is a bottom plan view of FIG. 4, the top plan view being the same as shown in FIG. 2.
